(57) **CLAIM**

The ornamental design for a car roof rack clamer, as shown and described.

DESCRIPTION

FIG. 1 is a perspective view of a car roof rack clamer of the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a use schematics view of a car roof rack clamer; and,

FIG. 9 is another use schematics view of two car roof rack clampers.

In the drawings, the broken lines in FIGS. 8 and 9 depict portions of a vehicle and form no part of the claimed design.
